UNITED STATES PATENT OFFICE

ARTHUR H. MANN, OF NYACK, NEW YORK, ASSIGNOR, BY MESNE ASSIGNMENTS, TO
MORSE BOULGER DESTRUCTOR CO., A CORPORATION OF DELAWARE

APPARATUS FOR DESTROYING WASTE

Application filed September 27, 1926. Serial No. 137,854.

This invention relates to apparatus for destruction of waste and infectious material, and among other objects aims to provide an improved apparatus of this character which will quickly destroy the waste and infectious material without scattering or disseminating the same either in the apparatus or the outside air.

These and other objects will be more fully set forth and described in the following specification and shown in the accompanying drawings in which

Fig. 1 is a vertical section through one embodiment of my improved apparatus.

Fig. 2 is a vertical section along the line 2—2 of Fig. 1.

Fig. 3 is a vertical section along the line 3—3 of Fig. 4 showing a modification.

Fig. 4 is a vertical section along the irregular line 4—4 of Fig. 3.

Like numerals refer to like elements throughout the drawings in which 10 indicates generally a furnace constructed of refractory tile or brick and encased in suitable heat insulating and protecting materials as illustrated in Fig. 1.

The front wall 10^a of the furnace is apertured to provide a burner opening 10^b in alignment with the fuel supply nozzle generally indicated by numeral 11. Projecting upwardly from the base or floor 10^c of the furnace is a supporting and separating partition 12 forming with the end wall 10^a an ash pit 10^d. At the top of the ash pit and extending between the partition 12 and the front wall 10^a is the grate 13 of conventional construction, the same being located below and adjacent to the fuel opening 10^b, as shown in Fig. 1. A suitable charging opening is indicated in dotted lines and designated by numeral 10^e, the same being arranged in a side wall to permit charging of rubbish or waste upon the grate 13; also to permit removal of clinker or accumulated incombustible material from the grate.

Located rearwardly of the grate 13 and slightly thereabove is the arched hearth 15 extending rearwardly from the partition wall 12 and near the side walls of the furnace 10. A charging opening 10^f is pro-

vided in the top of the furnace, the same being normally closed by a cover 16. This opening is located above the arch 15 to permit charge of wet waste, garbage or the like upon the hearth 15. The hearth terminates some distance short of the rear end wall 10^g of the furnace.

Located below the level of the hearth 15 is a second arched hearth 17, which extends forwardly from the rear end wall 10^g to a point beneath the rear end of the hearth 15, a passage 10^h being provided therebetween leading to the combustion or settling chamber 10ⁱ, which underlies the hearth 15, as shown in Fig. 1. The arched hearth 17 is preferably inclined upwardly from the end wall 10^g to resist removal or carrying away of the infectious material deposited thereon under the influence of the draft during combustion. Indicated in dotted lines is a charging opening 10^j in substantial alignment with the hearth 17 to permit charging and cleaning of the same when desired.

In the end wall 10^g is provided the outlet passage 10^k leading to the stack 18. A chamber or passage 10^l is provided beneath the hearth 17 and affords not only a means of communication between the chamber 10ⁱ and the outlet passage 10^k, but also provides additional space for thorough combustion of the gases generated in the furnace and for settling of any foreign matter carried thereby.

Suitable clean-out ports 10^m are provided in the side wall, as indicated in dotted lines in Fig. 1, these ports being equipped with closures or doors 20, as shown in Fig. 2, for example. The charging openings 10^e and 10^f are also provided with suitable closures as indicated in dotted lines by numeral 21. (See Fig. 2.)

In the use of the apparatus described and the practice of my process, the waste, as from a tuberculosis institution, for example, is preferably segregated or classified roughly into three classes; first, what is termed dry rubbish, this being generally highly combustible and capable of quick ignition and readily supporting combustion. The second class is termed wet waste and consists of

garbage or the like which is more or less moist, and which it is desirable to subject to a species of distillation in order to expedite and enhance combustion thereof. The third class is a class of highly infectious material, which may be more or less moist, such as sputum cups and the like, which are highly dangerous to handle, and which preferably are subjected to high intense heat, which 10 almost immediately sterilizes the waste and brings it to combustion and destruction in a relatively short time without permitting the carrying of infection or germs by the draft or solids carried by the gases to points 15 outside the furnace where infection might result.

The first class of waste is charged upon the grate 13, the second is charged through the opening 10^e upon the hearth 15, and the 20 third is deposited or charged upon the hearth 17. The rubbish or relatively dry waste quickly ignites from the burner flames injected through the opening 10^e, and the heat generated by the combustion of this 25 rubbish is added to the heat of the gases of combustion from the burner and the accumulated heat is passed over and contacts the wet waste upon the hearth 15. This is brought to a combustible condition by this 30 heat action and the heat of its gases generated together with such combustion as takes place is also added to the heat to which it is subjected, and the resultant cumulative heating draft or current is directed upon 35 the infectious waste upon the hearth 17, which it is forced to contact by the reversal in flow, which occurs as it is directed toward the passage 10^h. This reversal in flow also 40 has a tendency to slow down the velocity of the draft and the relatively large space above the hearth 17, coupled with this checking of the velocity, permits an intimate commingling of the previously generated gases, and further propagation of the combustion. 45 This results in the production of an intense heat which is directed as described upon the infectious waste, which is thereby quickly rendered sterile and brought to a combustible condition and then burned, the gases resulting 50 from its heating being carried with the previously generated gases into the settling and combustion chamber 10ⁱ, which may be termed the final combustion chamber, where such combustion may be completed and made substantially thorough. At 55 the same time added space is provided for the expansion of the gases which checks their velocity and permits settling of suspended solids or the like in the bottom of the chamber 10ⁱ where, if it is combustible it may burn, if not, where it may be readily removed. This final combustion chamber 10ⁱ being located beneath the hearth 15 heats the 60 same from beneath and enhances and accelerates the combustion and distillation of the 65

wet waste placed thereon, so that an added heating effect is imparted to such wet waste through this sub-heating of the hearth.

From the settling chamber 10ⁱ the gases 70 pass out through the chamber 10^j to the stack, serving to heat the hearth 17 from beneath, increasing the rapidity and thoroughness of the combustion of the infectious waste carried thereon.

The inclination of the hearth 17 upwardly 75 from the end wall 10^g resists carrying or displacement of the infectious waste from the hearth prior to its sterilization and substantial destruction.

The clean-out ports 10^m may be availed 80 of to remove deposited matter from the bottom of the chambers 10ⁱ and 10^j, and the ash may be removed through a similar clean-out port in the ash pit 10^d, while such clinker or accumulation of non-combustibles as accumulate upon the grate 13 and hearth 17 may be removed from time to time through the ports 10^e and 10^j as will be obvious.

In Figs. 3 and 4 I have illustrated another embodiment of my invention which also may be used to practice the same process. In these figures I have designated the furnace generally by numeral 100. The construction is generally similar to that illustrated in Figs. 1 and 2, and I have applied the same numerals to the same structural features in Figs. 3 and 4. The second construction differs in that no gas or other burner is provided, but if necessary, added combustibles, such as coal, coke or the like are charged with the dry rubbish upon the grate 13. I have illustrated a charging duct 100^e as extending to an upper level A, such as an upper floor, with a suitable cover 116 for the duct at such floor level.

Also, I provide a secondary source of heat comprising a grate 25 having a charging opening 25^a associated therewith as indicated in dotted lines in Fig. 3. A supporting abutment 26 extends upwardly from the base of the furnace and is spaced from the partition or abutment 12 a sufficient distance to support the grate 25 and to provide an ash pit 25^b therebeneath.

It may be desirable in some instances to utilize this secondary source of heat in which event fuel is charged thereon and combustion maintained. The heat from such combustion serves to increase the heating of the hearth 15 being located therebelow, and the gases from this secondary combustion are added to those previously generated and in their passage through the final combustion chamber 10ⁱ they pass along the hearth 15 first, and then beneath the hearth 17, adding to the heating of such hearths, as will be obvious. From the outlet passage 10^k leads a laterally directed outlet 118, the flow through which is regulated by a sliding damper 30 which may 130

be used to control the draft in the furnace in well known manner.

It will be apparent that my invention is susceptible of modification and variation, and I do not wish to be restricted to the forms described and shown, save as defined in the appended claims.

What I claim is:

1. A furnace of the character described comprising in combination a grate for the reception of relatively dry combustible waste, an elevated imperforate hearth extending from said grate and having associated therewith means to permit the deposit of moist and relatively combustible refuse thereon, said hearth being terminated short of the furnace wall in the direction of travel of gases of combustion to provide a downwardly extending passage therefor, and a second imperforate hearth located below said passage and having means by which infectious material may be deposited thereon and positioned relatively to the first hearth to provide a passage for gases of combustion above said second hearth, said furnace being constructed and arranged to provide a space beyond said passage over the second hearth enlarged in cross section relative to said passage to check the velocity of the gases and permit the settling out of particles carried thereby.

2. A furnace of the character described comprising in combination a grate for the reception of relatively dry combustible waste, an elevated imperforate hearth extending from said grate and having associated therewith means to permit the deposit of moist and relatively combustible refuse thereon, said hearth being terminated short of the furnace wall in the direction of travel of gases of combustion to provide a downwardly extending passage therefor, and a second imperforate hearth located against said furnace wall below said passage to provide a space below the first hearth for the travel of gases of combustion, said second hearth being inclined against the flow of gases to resist the tendency of said flow to carry particles from said second hearth, and means by which infectious material may be deposited on said second hearth, said furnace being constructed and arranged to provide a space beyond said passage over the second hearth enlarged in cross section relative to said passage to check the velocity of the gases and permit the settling out of particles carried thereby.

3. A furnace of the character described comprising in combination a grate for the reception of relatively dry combustible waste, an elevated imperforate hearth extending from said grate and having associated therewith means to permit the deposit of moist and relatively combustible refuse thereon, said hearth being terminated short of the

furnace wall in the direction of travel of gases of combustion to provide a downwardly extending passage therefor, and a second imperforate hearth located against said furnace wall below said passage to provide a space below the first hearth for the travel of gases of combustion, said second hearth being inclined against the flow of gases to prevent the liquid refuse from running off said hearth under the influence of gravity and having a wall at its lower end to prevent escape of such liquid at that end, and means by which infectious material may be deposited on said second hearth, said furnace being constructed and arranged to provide a space beyond said passage over the second hearth enlarged in cross section relative to said passage to check the velocity of the gases and permit the settling out of particles carried thereby.

In testimony whereof, I have signed my name to this specification.

ARTHUR H. MANN.
